WATER HEATER

Lawrence Richardson, Melrose, Mass.

Application August 30, 1930, Serial No. 478,867

19 Claims. (Cl. 122—434)

This invention relates to water heaters and more particularly to locomotive feed water heaters; and is especially applicable to, and useful in connection with heating water in, the tenders 5 of locomotives, such an embodiment of the invention being hereinafter disclosed by me.

One of the primary objects of the invention is to improve locomotive feed water heating generally and to utilize to the full the exhaust steam 10 of the locomotive proper and of its auxiliaries, and more especially to accomplish these ends by an improved form of storage heater.

Other objects involve: the substantial reduction of the weight of feed water heating equipment generally; the reduction or elimination of such weight on the engine unit of the locomotive; a substantial simplification in, and reduction of first and maintenance costs of, the heater itself and the steam, water and condensate connections 20 and lines thereto and therefrom.

Still another object is to heat and/or store feed water in progressive stages or at progressive temperatures, and especially by progressive or step-by-step utilization of the steam or other heating 25 medium, and further to accomplish this in a tender heater while still preserving a volume of the water therein sufficiently cold to be handled by the usual injector in case of feed pump failure.

Other objects and advantages, as to features of construction and operation will appear hereinafter.

How the foregoing, together with such additional objects and advantages as may be incident 35 to the invention, are attained will be clear from the following description, taken together with the accompanying drawings, in which drawings:

Figure 1 is a somewhat diagrammatic, broken out, side elevational view of the engine of a locomotive embodying my invention;

Figure 2 is a vertical, longitudinal section through the tender of the same locomotive, with certain parts shown in elevation and others diagrammatically; and

Figure 3 is a fragmentary section similar to the upper portion of Figure 2, but illustrating a modification of a part of the construction.

By reference to the drawings, it will appear that I have illustrated a locomotive having an engine 2, and a tender 3 in which I have embodied the present invention. The engine of the locomotive is equipped with a centrifugal water pump 4 driven by a turbine 5, steam being delivered to the turbine, as from a turret (not shown), 55 through pipe 6, valve 7 and pipe 8. The exhaust

from the turbine passes, through pipe 9, into main exhaust conduit 10 which leads from the valve chest 11 to the flexible connection 12 between engine and tender. A cross-connection 13 may be provided to connect the exhaust cavities 60 of the two valve-chests of the locomotive. Flexible connection 12 is, in turn, coupled to the steam pipe 14 leading to the heater in the tender. The water connections to the pump 4 are by way of the water outlet or withdrawal pipe 15, flexible 65 connection 16, pipe 17 and strainer 18. Leaving the pump, the water passes through pipe 19 and check valve 20 into the boiler 21.

The main tank or body 22 of tender 3 is divided by partitions 23 into a series of chambers 70 24, 25, 26 and 27, considered serially from the inlet 28 to the outlet 15, said chambers having communication, as by means of openings 29 covered by flap valves 30 which may be mounted on springs 31 of such pressure as to insure the 75 closure of gates or valves 30 but to permit opening thereof under the influence of forward surges, or slight pressure head, of water in the tender. I utilize this construction as a means, first, for segregating the chambers of water; second, for 80 insuring that the water work forward gradually, from the main compartment 24, as used, successively through the others to the withdrawal compartment; and third, for maintaining the hottest water always in the outlet compartment, 85 and step-by-step, cooler water in the others, so that there is a progressive replenishment of the hot water displaced or used, by cooler water.

It may here be observed that the compartments or chambers are also of progressively 90 smaller capacity, the cross-sectional area of the tender tank diminishing toward the forward or outlet end, by virtue of the coal floor 32, so that the outlet (hottest) compartment or chamber is really a substantially U-shaped water containant, 95 the leg of the U being the space 33 beneath the coal floor, or deck.

Now it will be evident that, as the water works toward the forward end of the tender, provision must be made for venting air in the chambers so as to prevent the building up of such pressure therein as would too greatly restrict the admission of water through valves 30. I have devised two ways of doing this. In Fig. 2, there will be seen a series of conduits or pipes 34, each one of which extends from a point near the top of the compartment to a point adjacent the bottom of the proximate rearward compartment, the rearmost compartment 24 being in communication with atmosphere by virtue of the inlet 28. Alter- 110

natively, as seen in Fig. 3, I provide small conduits 34a individually venting the several compartments to the atmosphere. While the latter device is slightly simpler, I prefer the former, as there is combined with it an added useful function, to wit: steam or heated air passing up through the water in any given chamber is taken off by pipe 34 at a point above the water level and, under its own pressure, discharges into the adjacent rearward chamber beneath the water level, thereby fully utilizing heat therein and also avoiding any possibility of discharging excess steam into the atmosphere which is obviously objectionable in railroad operation.

15 The heating unit, proper, is extremely simple, comprising, at it does, merely an extension 14a of pipe 14, lying substantially along the floor of the tender tank and extending through all but the rearmost of the partitions or walls 23. This 20 pipe or conduit 14a has a closure cap 14b at its rear end, and has, in the several compartments, perforations or holes 14c, 14d and 14e, respectively. It should here be observed that the cross-sectional area of the steam outlets is made 25 progressively smaller in each chamber serially rearward, either by making the apertures or holes smaller, or, as here shown, by making them fewer in number. The effect of this arrangement, coupled with the fact that there is naturally 30 greater resistance to the steam flow in proportion to the greater length of travel through the pipe, is to cause the greatest discharge of steam into chamber 27 and, step-by-step, less discharge into each of chambers 26 and 25, no steam being 35 delivered into chamber 24 (with the exception, possibly, of a small quantity through the last vent-pipe 34) so that the latter chamber has a relatively cold body of water therein suitable for use in the usual injector (not shown) in case of 40 pump failure.

From the foregoing it will be evident that by my invention the weight, complication, first cost, and expense of inspection, repair and maintenance of feed water heating equipment is very 45 materially reduced as compared with prior known devices; that a heating and segregation of the water by stages, or progressively, is attained in a very simple and effective manner; that the exhaust steam is utilized to the fullest extent, and 50 especially so in the form of construction shown in Figs. 1 and 2, in which each chamber is vented to the next cooler chamber; that the tender itself is utilized as the heater in an extremely simple manner and with the addition of a minimum of 55 additional apparatus; that the invention may be almost as readily applied to existing as to new equipment; and that, in general, the objects stated at the head of this specification are realized by a simple, inexpensive and rugged construction.

60 What I claim is:—

1. A locomotive feed water heater including a plurality of water containing chambers, and means for delivering steam into the heater including a conduit extending into a plurality of chambers, and outlet means in the conduit in each of the said chambers, the said steam delivery means being so arranged that more steam is delivered into one chamber than into another.
2. A locomotive feed water heater including a plurality of water containing chambers, and means for delivering steam into the heater including a conduit extending into a plurality of chambers, and outlet means in the conduit in each of the said chambers, said outlet means

being of greater effective capacity in one chamber than in another.

3. A locomotive feed water heater divided into a plurality of chambers disposed in a horizontal series, means providing substantially horizontal flow of water from one chamber to another substantially in one direction only, and means for delivering heating steam to chambers of the heater in different quantities respectively.

4. A locomotive feed water heater divided into a plurality of chambers disposed in a horizontal series, means providing substantially horizontal flow of water from one chamber to another substantially in one direction only, and means for delivering heating steam to chambers of the heater and in greater quantities to that chamber into which water flows from another.

5. A locomotive feed water heater divided into a plurality of chambers disposed in a horizontal series, means providing substantially horizontal flow of water from one chamber to another substantially in one direction only, and means for delivering heating steam to chambers of the heater and in greater quantities to that chamber into which water flows from another, together with means for taking water from the receiving or hottest chamber and delivering it to a point of use.

6. A locomotive feed water heater divided into a plurality of chambers disposed in a horizontal series, means providing substantially horizontal flow of water from one chamber to another substantially in one direction only, and means for delivering heating steam to chambers of the heater, together with means for venting one chamber to another in a direction opposite to the flow of water.

7. A locomotive feed water heater divided into a plurality of chambers disposed in a horizontal series, means providing substantially horizontal flow of water from one chamber to another substantially in one direction only, and means for delivering heating steam to chambers of the heater, together with means for venting one chamber to another in a direction opposite to the flow of water, said vent means including means for carrying excess steam from a hotter chamber to a cooler chamber.

8. A locomotive feed water heater divided into a plurality of chambers, means whereby flow of water from one chamber to another may take place substantially in one direction only, and a pipe for supplying heating steam to the heater extending into a plurality of chambers of the heater, and having a different number of outlet holes in different chambers.

9. A locomotive tender storage heater having a plurality of compartments disposed in a horizontal series; a tender water inlet to one compartment; means whereby water may pass successively from said compartment to the others, serially; means for delivering water from the last of the said series of compartments into the locomotive boiler, and means for passing heating steam into the water in all except the first-identified compartment in progressively decreasing amounts in serial order reverse to the order of water-flow.

10. A locomotive feed water heater comprising a series of water storage compartments, means for conveying steam into a plurality of compartments to heat the water therein, means of substantially horizontal communication between the compartments for effecting flow of water serially from one compartment to another under the in-

- fluence of surging of the water induced by movements of the locomotive and for restricting reverse flow, and outlet means for taking heated water from the last compartment of the series.
- 5 11. A locomotive feed water heater comprising a series of water storage compartments, means for conveying steam into a plurality of compartments to heat the water therein, means of substantially horizontal communication between the compartments for effecting flow of water serially from one compartment to another under the influence of surging of the water induced by movements of the locomotive and for restricting reverse flow, and outlet means for taking heated water from the last compartment of the series, said means for effecting flow in one direction and restricting opposite flow including partitions with one-way gate means therein. 80
- 10 12. A locomotive feed water heater comprising a series of water storage compartments, means for conveying steam into a plurality of compartments to heat the water therein, means of substantially horizontal communication between the compartments for effecting flow of water serially from one compartment to another under the influence of surging of the water induced by movements of the locomotive and for restricting reverse flow, and outlet means for taking heated water from the last compartment of the series, said means for effecting flow in one direction and restricting opposite flow including partitions with one-way gate means therein. 85
- 15 13. A locomotive feed water heater comprising a series of water storage compartments, means for conveying steam into a plurality of compartments to heat the water therein, means of substantially horizontal communication between the compartments for effecting flow of water serially from one compartment to another under the influence of surging of the water induced by movements of the locomotive and for restricting reverse flow, and outlet means for taking heated water from the last compartment of the series, said means for effecting flow in one direction and restricting opposite flow including partitions with one-way gate means therein and vent means for each compartment. 90
- 20 14. A locomotive tender construction including a horizontally elongated water tank and a plurality of compartments therein arranged in a substantially horizontal series, means for introducing steam into a plurality of compartments to heat the water therein, and means for effecting a substantially horizontal flow of water serially from one compartment to another under the influence of surging of the water induced by movements of the locomotive and for restricting reverse flow. 95
- 25 15. A locomotive tender construction including a horizontally elongated water tank and a plurality of compartments therein arranged in a substantially horizontal series, means for introducing steam into a plurality of compartments to heat the water therein, and means for effecting a substantially horizontal flow of water serially from one compartment to another under the influence of surging of the water induced by movements of the locomotive and for restricting reverse flow. 100
- 30 16. A locomotive tender including a horizontally elongated water tank divided into a horizontal series of compartments, means providing substantially horizontal communication serially between the several compartments, whereby to provide for a substantially horizontal and serial flow of water from one compartment to the next under the influence of surging of the water induced by movements of the locomotive, means for restricting serial flow of water between said compartments in one direction, and means for conveying steam into a plurality of compartments to heat the water therein. 105
- 35 17. A locomotive tender construction including a horizontally elongated water tank and a plurality of compartments therein arranged in a substantially horizontal series, means for introducing steam into a plurality of compartments to heat the water therein, and means for effecting a substantially horizontal flow of water serially from one compartment to another under the influence of surging of the water induced by movements of the locomotive and for restricting reverse flow. 110
- 40 18. A locomotive tender construction including a horizontally elongated water tank and a plurality of compartments therein arranged in a substantially horizontal series, means for introducing steam into a plurality of compartments to heat the water therein, and means for effecting a substantially horizontal flow of water serially from one compartment to another under the influence of surging of the water induced by movements of the locomotive and for restricting reverse flow, together with means providing for venting of the space above the water in one compartment to another compartment below the water level therein in reverse flow with respect to the direction of water flow. 115
- 45 19. A locomotive tender construction including a horizontally elongated water tank and a plurality of compartments therein arranged in a substantially horizontal series, means for introducing steam into a plurality of compartments to heat the water therein, and means for effecting a substantially horizontal flow of water serially from one compartment to another under the influence of surging of the water induced by movements of the locomotive and for restricting reverse flow, the means for introducing steam into a plurality of compartments including means for heating the water to progressively greater degrees in the several compartments in the said serial order. 120
- 50 20. A locomotive tender construction including a horizontally elongated water tank and a plurality of compartments therein arranged in a substantially horizontal series, means for introducing steam into a plurality of compartments to heat the water therein, and means for effecting a substantially horizontal flow of water serially from one compartment to another under the influence of surging of the water induced by movements of the locomotive and for restricting reverse flow, the means for introducing steam into a plurality of compartments including means for heating the water to progressively greater degrees in the several compartments in the said serial order. 125
- 55 21. A locomotive tender including a horizontally elongated water tank divided into a horizontal series of compartments, means providing substantially horizontal communication serially between the several compartments, whereby to provide for a substantially horizontal and serial flow of water from one compartment to the next under the influence of surging of the water induced by movements of the locomotive, means for restricting serial flow of water between said compartments in one direction, and means for conveying steam into a plurality of compartments to heat the water therein. 130
- 60 22. A locomotive tender including a horizontally elongated water tank divided into a horizontal series of compartments, means providing substantially horizontal communication serially between the several compartments, whereby to provide for a substantially horizontal and serial flow of water from one compartment to the next under the influence of surging of the water induced by movements of the locomotive, means for restricting serial flow of water between said compartments in one direction, and means for conveying steam into a plurality of compartments to heat the water therein. 135
- 65 23. A locomotive tender including a horizontally elongated water tank divided into a horizontal series of compartments, means providing substantially horizontal communication serially between the several compartments, whereby to provide for a substantially horizontal and serial flow of water from one compartment to the next under the influence of surging of the water induced by movements of the locomotive, means for restricting serial flow of water between said compartments in one direction, and means for conveying steam into a plurality of compartments to heat the water therein. 140

LAWRENCE RICHARDSON.
